Specification of Letters Patent.

Patented Mar. 9, 1920.

Application filed January 25, 1919. Serial No. 273,095.

To all whom it may concern:

Be it known that I, GEORGE A. BURBEY, a citizen of the United States, residing at Spokane, in the county of Spokane and State 5 of Washington, have invented new and useful Improvements in Boxes, of which the following is a specification.

This invention relates to improvements in boxes and has to do more particularly with 10 boxes formed from blanks, foldable into box formation.

One of the objects of this invention is to provide an initially flat blank, adapted to be shipped flat by the maker, and provided 15 with means for connecting portions of the blank so that while the retailer can stack the blanks in collapsed form, the blanks will nevertheless be capable of being folded from a collapsed, into box formation, without the 20 necessity of connecting any portion of the blank with any other portion thereof.

A further object is to provide the blank, of which the box is formed, with sections adapted to form closures for the box body, 25 one closure, in the preferred form of the invention, being designed to remain closed, and the other closure performing the function of a door which may be opened or closed as access is had to the interior of the box.

30 A further object is to provide one or more closures with novel means whereby the closures will, when closed, coact with the walls of the box body in a manner to stiffen, rigidify and otherwise hold the body to 35 form, without imposing any strain on the hinged connection of the closure in the performance of this particular function.

My invention is especially directed toward 40 and includes the idea of fancy boxes particularly adapted for use in connection with articles to be contained therein which are of a delicate nature, such for instance as ladies' hats, and wherein the element of attractiveness is important not only as regards 45 the exterior, but also the interior thereof. Thus it is a feature of this invention to provide a lining for the sections of the box, and for the door and closure therefor, such as will not only serve to present an attractive 50 interior appearance but which will also render the box substantially dust proof.

A further feature of the invention is to form the blank of what is known in the trade as "corrugated board," which consists 55 of an intermediate layer of corrugated paper

faced on both sides by card or straw board sheets suitably secured to the intermediate layer of corrugated paper. A special feature resides in disposing the corrugations in a manner so that they will extend in one direction in all the sections, namely, both in the box forming and closure forming sections. 60

The invention has many other features and objects which will be more fully described in connection with the accompanying drawings and which will be more particularly pointed out in and by the appended claims. 65

In the drawings:—

Figure 1, is an exterior view of the finished blank as it would appear when being shipped by the maker.

Fig. 2 is a view of the interior side of the blank.

Fig. 3, is a perspective view of the blank connected, and partially collapsed, as it would appear after being assembled by the retailer.

Fig. 4, is a perspective view of the box 80 showing the form it would take when adjusted into box formation, the closure and door being open.

Fig. 5, is an enlarged sectional view on line 5—5 of Fig. 2, showing the detailed 85 construction of one edge portion of a section.

Fig. 6, is a sectional view on line 6—6 of Fig. 2, showing the detail manner of scoring the blank into separate box forming sections 90 and illustrating the appearance when the sections are in flat formation.

Fig. 7, is a similar view illustrating the appearance of the same sections when adjusted into angular relation with respect to 95 each other.

Fig. 8, is a sectional view on line 8—8 of Fig. 4, illustrating the manner in which the lining of the box and door sections coact, when the door is closed, to render the box 100 substantially dust proof.

Like characters of reference designate similar parts throughout the different figures of the drawings.

As shown, 1 designates a paper or like 105 blank which is substantially T-shaped in form, the stem being divided into box forming sections 2, 3 and 4, and the head being sub-divided into a box forming section 5, and into closure and door sections 6 and 7, 110

- respectively. The stem is scored at 8, 9 and 10, and the head is scored at 11 and 12. It is a feature of my invention to form the entire blank of one sheet of paper, the scored portions dividing the sheet into a plurality of integrally hinged sections. In the specific form shown, the section 2, which is provided with a handle 13, forms the top box body section, section 3, one side section, section 4, the bottom section, and section 5, the remaining side section. Thus when the sections are adjusted into box formation, the resulting box body is open ended, and the closure 6, which is intended to be permanently closed and fastened, closes one end of the box while the door 7, which provides for ready ingress to the box, closes the other open end thereof. It is also a feature of this invention to form the blank of corrugated board with the corrugations extending in one direction, such direction being vertically with respect to the sides and closures thereby materially adding to the strength thereof.
- When the connected blank shown in Fig. 3, is adjusted into box formation as shown in Fig. 4, the natural tendency would be for the box to seek the semi-flat position shown in Fig. 3, after having occupied such position for a considerable time in stock or storage. Now it is a novel feature of my invention to provide one of the closures, preferably that one which is least frequently opened, with means coacting with the box sections to sustain the latter in a true box forming, or in the present case, rectangular position, not only to prevent the box from collapsing, but also to insure the door an accurate closing fit against the edges forming the remaining open end of the box.
- Referring specifically to this feature, the closure 6, has secured to its inner face a stiffening plate 14, which if of corrugated material, will have its corrugations running or extending at right angles to the direction of the corrugations of the closure proper, as indicated at 15. This disposition serves to strengthen the closure itself. However, the stiffening plate 14 is proportioned so that its edges 16 will engage the interior faces of the box forming sections thereby securely holding said sections in true rectangular relation, as shown in Fig. 4, when the closure 6 is in a closed position. It will be understood that normally, in the use of the box, and after it has once been set up, the closure 6, when once closed and fastened, will remain closed. Thus, the box contents will always be accessible by opening the door 7, without thereby weakening the box and permitting it to partially or wholly collapse. Further, as the stiffening plate or means has an edge for engagement with each box forming section, this closure 6 will perform its stiffening function without in any way weak-

ening its integral hinged connection with side 5, the strain being wholly imposed on the plate 14, itself.

In a box, foldable or adjustable into form from a folded or collapsed position, and held to form by one of its integral sections, I consider it new and novel to provide an integral door which is capable of being opened or closed at will of the user.

I have shown means for fastening the closure 6, in a closed position, and which means is accessible only interiorly of the box, said means consisting of paper or like disks and strings, the specific novelty of which is not herein claimed. The closure 6 has two disks 17, on its inner face, each provided with a fastening string adapted to be wound about companion disks 19, on the inner face of box section 3. The door 7, is provided with one disk 20, on its exterior, having a fastening string 21, adapted to be wound about a disk 22, on the exterior of box side 3. Thus the disposition of the fastening strings will indicate to the user the difference between the closure 6 and the door 7, at a glance.

As shown in Fig. 5 what is known in the trade as "corrugated board" consists of an intermediate sheet of corrugated paper 23, faced on both sides with card or straw board sheets 24. Thus the exposed edges would, unless covered, present rough and unfinished edges. I will now detail the novel manner in which the box blank is exteriorly covered, preferably with an especial view of decoration, in order to conceal the unattractive foundation material.

A single sheet of decorative paper 25 is pasted or otherwise secured to the exterior of the blank 1, throughout the area thereof. Abreast of the scored portions, as shown in Fig. 6, there is a degree of slack, as indicated at 26, and the paper is free from the blank along these scored portions. Thus, when the sections of the blank are bent at right angles to each other, as shown in Fig. 7, the slack will permit the cover paper 25 to fit snugly about the corner lines of the box and present a neat and attractive appearance. As will be seen in Fig. 5, the marginal portion of the covering paper 25 is extended about the edge of the board, as indicated at 27, and thence the paper is overlapped onto the inside face of the section, as indicated at 28. At the end junctures of the covering paper with the scored portions, the former is notched, as at 29, in Fig. 2. It will be understood that at each section, the covering paper will be attached in the same manner as described in connection with the specific portions of the drawing just referred to.

The covering paper 25, is provided with a connecting flap 29' which is adapted to be secured, as by pasting, for instance, to the portion marked 30, of section 5. This serves

to connect the blank in a manner to permit the same to be collapsed into a flat condition, or adjusted into an operative position as shown in Fig. 4, without requiring any connection of parts. Thus, in Figs. 1 and 2, I have shown the blank as it would leave the factory, and in Fig. 3, I have shown the blank after it has been connected by the retail store and in shape either to be partially collapsed to economize space, or opened up, as in Fig. 4, for use. Therefore, in selling a hat, the box would be taken from stock in the adjustment shown in Fig. 3, and opened to form, and then the closure 6 would be closed and fastened and this would hold the box in form. The hat could then be inserted and then the door closed, and fastened.

I will next describe the manner in which the blank is lined so that when the blank is adjusted to box form, the lining will present a finished appearance and the interior of the box will be rendered attractive.

Each section is provided with a lining sheet, as 31, in connection with section 2, and this sheet will be pasted or otherwise secured to the inner portion of the section leaving the marginal portions free from connection with the section, as indicated at 32. These free margins 32 overlap the inturned margins 28, of the covering paper, as will be seen in Fig. 5. All four margins of the lining for each section will be free. Now in Figs. 6 and 7, it will be seen how these free margins 32 serve to overlap and form a finished edge at or abreast of the scored portion after the sections have been folded from blank relation, into rectangular relation, without requiring any attention on the part of the clerk or other salesman. In other words, these overlapping free margins automatically assume a crunched or shirred finished position along the interior of the scored portions.

In the case of the closure 6 and door 7, the outer paper covering is extended inwardly over the edge, as at 33, and the margin of the stiffening plate 14, overlaps the

margin 33. The lining section 34 extends over the plate 14 and the free margin 35 thereof is adapted to interpose itself between the finished edge 27 and the door or closure so that when either are closed, the interposed free margins tend to make the closure dust proof. Thus with this novel type of lining, the same is caused to perform two functions, namely, to act as a lining *per se*, and also as an automatic finisher for the scored portions and as a closure for the door portions.

My improved box is especially designed for use in connection with the sale of ladies' hats, but its utility as a fancy or useful box in other capacities will be apparent, and while I have herein shown one specific form of my invention, I do not wish to be limited thereto except for such limitations as the claims may import.

I claim—

1. In a fancy box, a paper blank scored into sections adapted to be folded into box formation, the outer faces of said sections having a decorative covering extending about the edges of said sections and overlapping the inner faces thereof, the inner faces of said sections having decorative covering meeting the overlapped portions of the outer faces and the edges or margins of the decorative covering of said inner faces being free from said sections.

2. In a blank for making a fancy box, a blank body divided by score lines into a plurality of box forming sections, a separate lining for each section and the marginal portions of the linings along the scored portions being free, whereby when the sections are disposed in angular relation the adjacent free marginal portions will interlap and indiscriminately crunch and form a finished decorative edge along the line of score of the box.

In testimony that I claim the foregoing as my own, I hereby affix my signature.

GEORGE A. BURBEY.
